UNITED STATES PATENT OFFICE.

GEORGE P. FOOTE, OF DANBURY, CONNECTICUT.

HAT-FLANGING MACHINE.

1,108,730.

Specification of Letters Patent. Patented Aug. 25, 1914.

Application filed March 5, 1914. Serial No. 322,585.

To all whom it may concern:

Be it known that I, GEORGE P. FOOTE, a citizen of the United States, residing in the city of Danbury, county of Fairfield, State of Connecticut, have invented certain new and useful Improvements in Hat-Flanging Apparatus; and I do declare the following to be a full, clear, and exact description of the invention, such as will enable others skilled in the art to which it appertains to make and use the same.

This invention relates to certain new and useful improvements in hat flanging apparatus, and the primary object thereof is to provide means for steaming the brims of soft hats so as to soften the stiffening substance, and to equally or uniformly distribute such substance throughout the brim, and to prevent contact of the steam during the steaming process, with the crown or sweat band of the hat.

Further the invention has for its object novel and improved means for supporting the hat in position to enable same to be subjected to the steaming process and to allow the hat to be easily and quickly placed within and removed from the apparatus.

A still further object of the invention is to provide a device of the type set forth in which the steam is admitted and distributed in the most advantageous manner, and to also provide means which can be easily and quickly applied to and removed from the hat for protecting same during the steaming process and to also enable the brim to be shaped after steaming thereof.

In the drawings: Figure 1 is a top plan view of the invention; Fig. 2 is a section taken on the line $x-x$ of Fig. 1; Fig. 3 is a bottom plan view of the filler block in position within the hat; and Fig. 4 is an enlarged fragmentary sectional view of the forming rim and cover showing the dowel pin connection therebetween.

In proceeding in accordance with this invention a steam box 1 is employed which has an open-top and a closed bottom 2, ledges 3 being provided at the top of the box and projecting within the box interior. A metallic foraminous steaming receptacle 4 has a closed bottom 5 and an open top the free end portions of the sides and ends of which receptacle are bent outwardly to form flanges 6 which seat on the ledges 3 and support the steaming receptacle within the box so that a steam space is provided between the bottom

of the receptacle and the bottom of the box and also between the sides and ends of the receptacle and between the sides and ends respectively of the box.

60

The box bottom 2 is provided with a series of outlet pipes 7 which branch from a main pipe 8 the latter being inclined so as to drain off the condensation water of the steam. The steam supply pipe 9 has a nozzle 10 which projects through the box bottom 2 and has a head 11 affixed to its free end, the head being closed at its outer end and provided with radial or lateral steam passages 13, whereby it will be seen that the steam will not be projected directly up against the hat, but will be projected horizontally instead, so as to evenly distribute the steam throughout the area of the box bottom.

70

The means for supporting the hat and protecting the crown and sweat band thereof consists of a former rim 14 exteriorly shaped to conform to the shape which the finished brim is to possess; a filling block 15 which projects within the hat opening, and a cover 16, 80 which engages over the hat crown and which has the free edges of its sides seating on the former rim 14 and removably connected thereto by dowel pins 17. The filling block 15 has an annular groove 18 formed in its 85 under face to provide finger holds which enable the block to be placed into and removed from operative position. The periphery of the filling block 15 has a strip of felt 19 secured thereto, a flange 20 extending 90 outwardly from the strip, for a purpose now to be set forth.

95

In operation, the rim 14 is first placed about the hat in the position shown in Fig. 2, after which the filling block 15 is inserted within the head opening of the hat, the felt strip 19 engaging the sweat band S of the hat and the flange 20 of said strip extending over the points of juncture of the sweat band with the base of the hat 100 brim so as to seal the joint formed by sewing of the sweat band to the brim base. The cover 16 is then placed in position on the rim 14 and is held in such position by the dowel pins 17 above mentioned, in which position of the parts, as depicted in Fig. 2 of the drawings, the entire hat is protected except the major portion of the brim. The operator, as is evident, merely inserts the hat, held and protected in the manner described, within the steam receptacle so that the filling block 15 and the flange 20

105

110

of the felt strip 19 seat on the bottom 5 of the receptacle. Steam which enters the receptacle will be horizontally distributed and will pass through the perforations of 5 the steam receptacle and contact with the hat brim, in an evident manner. The space between the side and end walls of the box and receptacle respectively not only enables a uniform entry and distribution of the 10 steam within the receptacle, but also provides walls, which will trap the water of condensation and allow same to gravitate downwardly to the bottom 2 where the water will be drained off by the branches 15 7 and pipe 8 in an obvious manner. The steam, as is evident, only acts on the brim and the latter when softened causes the stiffening substance to be uniformly distributed, and the operator removes the 20 forming ring from the receptacle and by his hands manipulates or works the softened brim so that it conforms to the shape of the rim.

The felt lining or strip 19 which overlaps 25 the sweat-band of the hat not only causes the removable filling block to fit snugly within the hat crown and to hold the hat firmly in place, but the overlapping part or flange 20 protects the sweat-band so that 30 the steam cannot affect it.

What is claimed is:—

1. In a hat flanging apparatus, a steam box having its bottom provided with means for discharging water of condensation, a 35 steaming receptacle depending within said box and having a perforated bottom which latter is spaced from the bottom of the box, the side walls of said receptacle being also perforated and spaced from the re- 40 spective side walls of the box, and a steam inlet pipe extending up through the box bottom and terminating within the space between the bottom of said box and receptacle, said pipe being closed at the top and 45 having lateral perforations whereby the steam will be initially discharged into said space in substantially a horizontal plane.

2. In a hat flanging apparatus, a forami- 50 nous steaming receptacle and protecting means for the hat consisting of a forming rim which engages the inner side of the hat brim, a filling block having a felt strip secured to its periphery to engage the sweat 55 band and a flange which projects outwardly from said strip and across the joint between the sweat band and the brim and a cover

which incloses the hat crown and engages said rim.

3. In a hat flanging apparatus, a forami- 60 nous steaming receptacle and protecting means for the hat consisting of a forming rim which engages the inner side of the hat brim, a filling block having a felt strip secured to its periphery to engage the sweat 65 band and a flange which projects outwardly from said strip and across the joint be- 70 tween the sweat band and the brim and a cover which incloses the hat crown and en- gages said rim, said block and flange of the felt strip being for seating engagement on the bottom of said receptacle.

4. In a hat flanging apparatus, a steam 75 box, a foraminous steaming receptacle pro- jecting within the box and having its bot- 80 tom and sides spaced from the bottom and sides respectively of the box, and means in the space between the bottoms of the box and receptacle for supplying steam to the interior of the box to enable same to sim- 85 ultaneously enter the receptacle from the bot- 90 tom and sides of the receptacle.

5. In a hat flanging apparatus, a steaming 95 receptacle, and protecting means for the hat consisting of a forming rim, a filling block for insertion in the head opening of 85 the hat, and means borne by said block for 90 engaging the sweat band and sealing the joint between the sweat band and the hat brim and a cover for the hat crown engaged with the rim.

6. In a hat flanging apparatus, a steaming 100 receptacle, and protecting means for the hat consisting of a forming rim, a filling block for insertion in the head opening of 95 the hat, and means borne by said block for 90 engaging the sweat band and sealing the joint between the sweat band and the hat brim and a cover for the hat crown engaged with the rim, said block and means 105 being for seating engagement on the recep- 100 tacle bottom.

7. In a device of the type set forth, a forming rim, a filling block within the rim, a cover on the rim, and means borne by the rim to engage the sweat band and to extend 105 over the sewed edge of the latter.

In testimony whereof I affix my signature in presence of two witnesses.

GEORGE P. FOOTE.
